[57] CLAIM

The ornamental design for a combined refillable eraser tips and holder therefor, as shown and described.

DESCRIPTION

FIG. 1 is a front elevational view of a combined refillable eraser tips and holder therefor showing my new design; FIG. 2 is a right side elevational view, the left side being a mirror image thereof;

FIG. 3 is a rear elevational view;

FIG. 4 is a top plan view;

FIG. 5 is a bottom plan view;

FIG. 6 is a right front perspective view;

FIG. 7 is a cross-sectional view taken along line 7—7 in FIG. 1; and,

FIG. 8 is a cross-sectional view taken along line 8—8 in FIG. 1.
